UNITED STATES PATENT OFFICE.

HENRY SCHOFIELD, OF SHEFFIELD, ENGLAND.

GRATE FOR THE FURNACES OF STEAM-BOILERS.

No. 899,910.

Specification of Letters Patent.

Patented Sept. 29, 1908.

Application filed November 23, 1907. Serial No. 403,466.

To all whom it may concern:

Be it known that I, HENRY SCHOFIELD, a subject of the King of Great Britain and Ireland, residing at 267 Stannington road, 5 city of Sheffield, England, have invented certain new and useful Improvements in Grates for the Furnaces of Steam-Boilers, (for which I have applied for a patent in Great Britain, No. 1,976, January 26, 1907; France, 10 No. 46,138, September 14, 1907; Spain, No. 8,261, September 13, 1907; Russia, No. 33,416, September 4, 1907,) of which the following is a specification, reference being had to the accompanying drawing:

15 This invention relates more particularly to the construction of a furnace floor the arrangement of the bars in relation to the longitudinal air conduits located underneath them, through which air, or a mixture of air 20 and steam, is supplied for the purposes of combustion; and it also refers to the construction of the furnace bridge. They are 25 illustrated in the annexed sheet of drawings in which

30 Figure 1, is a plan, and Fig. 2, side elevation of four single furnace bars in position across the two supporting air chambers, and also showing the position of steam pipe and jets. Fig. 3, is a plan, elevation, and under- 35 side of a double length furnace bar. Fig. 4, vertical section of improved bridge.

35 In carrying out that part of the invention referring to the floor of the furnace, a number of trough shaped air conduits A, open at the top and the front end and closed at the far end, and having openings through the base and a hit-and-miss slide A², by which 40 ash and the like can be cleared from the interior, are supported in the furnace of the boiler in the usual position of a furnace floor. These conduits receive compressed 45 air, or air and steam, from pipes A³, provided with jet openings, at the front end and convey it to all the numerous apertures E, through the floor of the furnace above, and so into the fuel to promote combustion.

50 The floor is composed of furnace bars B, either cast singly as the four shown in Fig. 1, or in multiples such as the two shown in Fig. 3, connected endwise arranged across and supported by the conduits. The single bars are made to reach across and rest upon the top edges of one conduit, and the lower part of the bar to fit within it, as

shown, for which purpose the bars are 55 formed with steps or abutments at C. Slightly projecting faces D, are cast on each side of the bars which form abutments for the adjacent bars, and determine the length and width of the narrow vertical air 60 passages E, through the floor of the furnace, and also prevent any displacement of the bars in relation to each other. Upon the ends of the bars which are next to the side of the furnace F, are projections G, to continue the 65 floor surface up to the furnace side. By arranging the furnace bars transversely to the furnace and to the air conduits, cross bars or like supports (required with longitudinal bars) are dispensed with, as also 70 are the special bars generally required for the furnace sides, and the transverse air openings so constructed give a better result in the regulation of the air-supply to the fuel from 75 end to end of the furnace than do longitudinal openings.

The second part of my invention relates to the hollow bridge for the additional supply of heated air, in combination with the improved floor, and is shown in Fig. 4. It 80 consists of a cast iron air passage H, tapering upwards, and open at the top and bottom which is not novel *per se*, the lower opening being provided with a valve I, to regulate the admission of air and the front 85 having ribs or gills. It has been usual to protect both sides of such metal bridges from the burning effects of heat from the furnace, with brickwork such as J, but it is found from experiments that brickwork 90 facing the furnace K, is unnecessary, as the current of air passing through the bridge prevents the metal being burned; the air passing through is also rendered much 95 hotter without the brickwork, and consequently is more effective in causing the combustion of the unburned products when passing over the bridge, I therefore omit the brickwork on the furnace side of the upper portion H² leaving it and its gills L, open 100 to the action of the fire.

Having now particularly described my invention, I declare that what I wish to claim as novel and protect by Letters Patent, is:—

In steam boiler furnaces the combination with longitudinally extending trough shaped air conduits having downwardly

converging walls and having their upper edges flanged outwardly, of transversely arranged fire bars having converging depending portions conforming to and fitting closely within the conduits, and having end projections which rest on said conduit flanges, said fire bars being formed with vertical and inclined spacing abutments

producing vertical tapering air passages substantially as described.

In witness whereof I have hereunto set my hand in presence of two witnesses.

HENRY SCHOFIELD.
